UNITED STATES PATENT OFFICE

2,511,767

ABDOMINAL SUPPORT

Cora L. Brenton, Jefferson City, Mo.

Application June 10, 1948, Serial No. 32,119

2 Claims. (Cl. 2—41)

1

My invention relates to new and useful improvements in abdominal supports, or the like, and more particularly to the type of support which is in the nature of a splint adapted for engagement with and use on a corset or foundation garment, the primary object of the invention being to provide a device of the character mentioned particularly applicable to use in connection with women who have weakened abdominal muscles.

A further object of the invention resides in the provision of a splint or the like formed of a rigid, non-flexible material, light in weight and provided on the inner face thereof with graduated corrugations, thereby providing spaces in which fatty portions of the abdomen may be received.

A further object of the invention resides in the provision of a device of the character mentioned which will form a firm waist-line support and force the fatty portions of the abdomen downwardly and inwardly, thus flattening the abdomen of the wearer and spreading the extra flesh, but at the same time firmly supporting and uplifting the organs just above the pelvic bone. Such a device will be a solution to the problem of straight stays over a curved surface, eliminating the difficulty of corsets slipping up when the muscles are in action, and allowing freedom of the muscles and controlling them at the same time.

Still another object of the invention resides in the provision of a device which may be quickly and readily applied to or removed from a corset or foundation garment and one which is simple and durable in construction, inexpensive to manufacture and one which will be very efficient and useful in operation.

With these and numerous other objects in view, my invention consists in the novel features of construction, combination and arrangement of parts, as will be hereinafter referred to and more particularly pointed out in the specification and claims.

In the accompanying drawing, forming a part of this application

Figure 1 is a perspective view showing a corset or foundation garment applied to a female wearer, with my improved splint or abdominal support applied to use thereon and shown in dotted lines;

Figure 2 is a fragmentary inside elevation of the corset or foundation garment, showing my improved splint or abdominal support applied thereto, and

Figure 3 is a vertical section through the device applied to use on the garment.

I am appreciative of the fact that there are now offered to the consuming public various types of abdominal supports for those persons possessing large, fleshy and heavy abdomens. Some of these devices are in the nature of elastic bands and some are in the nature of splints or stays fitted into bands or the like. These devices have not proven successful for all types and especially have not met the need and desire of women with large abdomen who with proper help can still look neat and at the same time have full freedom in the natural movement of the body. Corsets and foundation garments of the present day manufacture have not met the requirements. It is the purpose of my invention to overcome the difficulties now encountered and provide a device which will support the waist-line, provide for the reception of extra flesh and fat in the spreading and flattening of the abdomen and at the same time serve to uplift the organs just above the pelvic bone and remove obstructions to the bending of the body forward.

In carrying out my invention, I shall refer to the drawing, in which similar reference characters designate corresponding parts throughout the several views in which the numeral 1 designates a female to which is applied a corset or foundation garment 2. The person represented by the figure is presumptively large and fleshy with a large and heavy abdomen and foundation garments applicable to women of this type, in many instances, are formed in sections laced together, as shown at 3. My invention contemplates the use of a splint or support applicable to the front section of the corset or foundation garment 2, being shown in dotted lines on Figure 1.

The support of splint comprises a member 4 formed of plastic, or light metal, such as aluminum, having a flat outer face and a corrugated inner face. The corrugations represented by the numeral 5 are graduated in depth smaller toward the lower edge of the device and thus provide inner face projections on the support which are of graduating thickness or depth. These projections also taper thinner toward their outer ends, said ends of the projections terminating just short of the side edges of the member 4. These projections obviously form grooves therebetween and in the grooves there are formed openings or air passages indicated by the numeral 6.

The member 4 is formed slightly concavo-convex to better fit the abdomen and the garment 5 to which it is adapted to be attached and the

lower edges tend to converge toward a central lower projection 1 which forms a lower termination for the lowermost projection or corrugation 5 of the device.

The member 4 adjacent its side edges may be provided with openings 8 whereby the same may be laced, as shown at 9 to portions of the corset or foundation garment 2. If desired, any other form of means may be utilized to removably or permanently secure the device to the garment, as for instance, same may be riveted or similarly secured in place. Of course, the positioning of the device properly on the garment is important, since it must be positioned to properly support the abdomen. When so properly positioned, the top or uppermost rib or projection 5, which is the greatest in depth, will divide the diaphragm from the lower part of the abdomen and will form substantially the waist-line. This will tend to flatten the abdomen and force the flesh and fatty portions of the abdomen downwardly. In the spreading and flattening process, the extra flesh will find its way into the spaces between the projections or corrugations. Were it not for this construction, the fatty or fleshy portions of the abdomen would be forced upwardly above the waist-line, but this series of grooves or recesses between the projections or corrugations readily permits the flesh to be received therein. The air openings will prevent undue perspiration forming. The lowermost projection or corrugation on the splint, together with the portions of the garment supporting the latter will tend to uplift the organs just above the pelvic bone of the wearer. As the muscles of the body tend to pull downwardly, this device applied to the foundation garment, when the latter is applied to the body, will tend to hold up the muscles, lifting them firmly and permit the fleshy portions of the abdomen, which are spread and flattened, to be received in the grooves between the corrugations. To those experiencing the difficulties resulting from large and heavy abdomen, the device herein shown and described will prove of great value, comfort and support.

From the foregoing description of the construction of my improved abdominal support or splint, the construction thereof and application to use will be readily understood and it will be seen that I have provided a comparatively simple, inexpensive and efficient means for carrying out the various objects of the invention.

While I have particularly described the elements best adapted to perform the functions set forth, it is apparent that various changes in

form, proportion and in the minor details of construction may be resorted to, without departing from the spirit or sacrificing any of the principles of the invention.

Having thus described my invention, what I claim is:

1. An abdominal support comprising a plate adapted to be mounted on the abdominal portion of a garment, said plate being of concavo-convex formation between its side edges and having its lower portion tapered in width towards its lower end, the concaved face of said plate being presented rearwardly and formed with transversely extending ribs disposed one above another, said ribs having surfaces arcuate in vertical cross section and merging into grooves located between the ribs and having transversely arcuate walls, said ribs successively decreasing in thickness from the upper end of the plate towards the lower end thereof, the lowest one of said ribs being gradually feathered in thickness towards its lower edge and merging into the lower edge of the plate, and said plate being formed with ventilating openings leading from said grooves to the front surface of the plate.

2. An abdominal support comprising a plate adapted to be mounted on the abdominal portion of a garment, said plate having its rear face concaved transversely between its side edges and formed with transversely extending ribs disposed one above another, said ribs having surfaces arcuate in vertical cross section and merging into the walls of grooves located between the ribs and having transversely arcuate walls, said ribs successively decreasing in thickness towards the lower end of the plate and the lowest one of said ribs being gradually feathered towards its lower edge.

CORA L. BRENTON.
